I. W. CHERNOFF

CONTAINER

Filed Dec. 13, 1922

Patented Aug. 7, 1923.

1,464,127

UNITED STATES PATENT OFFICE.

IDA W. CHERNOFF, OF SAN FRANCISCO, CALIFORNIA.

CONTAINER.

Application filed December 13, 1922. Serial No. 600,748.

To all whom it may concern:

Be it known that I, Ida W. Chernoff, a citizen of the United States, residing at San Francisco, county of San Francisco, and State of California, have invented new and useful Improvements in Containers, of which the following is a full, clear, and exact specification.

My invention relates to containers and refers particularly to containers suitable for the carrying of powder compacts and other toilet preparations and articles.

The many advantages incident to the employment of face powder compacts over the use of the loose powder has led to a general adoption of the former, and the desirability of a convenient package, or container, is evident.

The object of my invention is a device, or container, capable of receiving and retaining a plurality of compacts, with proper compartments for a number of other articles, the whole being in a compact, simple and efficient form and size.

One feature of the container of my invention is an inter-member between the two casings, which is of such construction that it may be utilized as a means for carrying a variety of articles, such as cigarettes, hair pins, pins, nail sticks or any other desirable articles of small size.

The advantages of such a container will be evident upon a consideration. It contains not only a large white compact, a small rouge compact, an eyebrow pencil and a lip stick, but has properly divided and devised compartments for the other articles mentioned and to which reference has been made.

In a broad way, the device of my invention comprises two casings to the inner face of which a plurality of toilet articles are affixed, and an inter-member having compartments for other articles as mentioned above.

In the particular form of the device of my invention, shown in the accompanying drawings, similar parts are designated by similar numerals.

Figure 1 is a perspective view of one form of my device in closed position.

Figure 2 is a top plan view of Figure 1 in open position, partly broken away for purposes of clearer description.

Figure 3 is a cross-section through the line 3—3 of Figure 2.

Figure 4 is a cross-section through the line 4—4 of Figure 1.

Figure 5 is a cross-section through the line 5—5 of Figure 2.

Figure 6 is a cross-section through the line 6—6 of Figure 2.

The particular form of the device of my invention, shown in the accompanying drawings, comprises the two exterior container casings 10 and 11, the hinge members 12, 12' of the casing 10 and the hinge members 13, 13' of the casing 11 forming a hinge engagement between the two casings by means of the pin 14. Pivotedly attached at 15, 15' to the pin 14 is a cigarette holder, or inter-member, composed of the two side fluted walls 16, 16' which are so formed as to produce a plurality of vertical compartments which are shown as connecting, but which may be entirely separate from each other as desired. A cover 17 capable of closing the cigarette compartments is pivotally attached to the cigarette holder at 18 and maintained in a normally closed position by means of the spring 19. Each compartment is capable of holding a cigarette 20, or other desired commodity or article.

A powder compact 21 is fixedly attached to the interior face of the casing 10 and a powder puff 22 may be placed thereon.

A mirror 23 is fixedly attached to the inner face of the casing 11, as is also a powder compact 24 upon which the powder puff 25 may be placed.

To the inner face of the casing 11 and on each side of the compact 24 is attached a plurality of spring holding members 26, 26' capable of receiving and retaining a lip stick or eyebrow pencil 27.

The two casings 10 and 11 are held in closed position by means of the depressible spring lock 28 having the releasing member 29 projecting through an opening in the casing 10, the pin 30 of the casing 11 being capable of placement through the opening 31 of the lock member 28 maintaining the casing in closed position, the inward movement of the releasing member 29 allowing the container to be opened.

A consideration of the above shows that the container of my invention, as described, is capable of carrying two affixed powder compacts, an affixed mirror, two removable toilet sticks, two removable powder puffs and a plurality of compartments for a large

variety of articles, and hence, presents a compact and convenient means for maintaining all of these toilet and other useful devices in an attractive and efficient manner.

5 I do not limit myself to the particular size, shape, number or arrangement of parts, as shown and described, as these are given simply as a means for the clear description of the device of my invention.

10 What I claim is:—

1. In a container, in combination, two casings, a plurality of toilet articles carried by the inner faces of the casings and an inter-member between the casings having spaced sides forming a container capable of having articles inserted therein.

15 2. In a container, in combination, two casings hingedly attached to each other, a plurality of toilet articles carried by the inner faces of the casings and an inter-member between the casings having spaced sides forming a container capable of having articles inserted through the top thereof.

20 3. In a container, in combination, two casings hingedly attached to each other, a plurality of toilet articles carried by the inner faces of the casings, an inter-member between the casings having spaced sides forming a container capable of having articles inserted through the top thereof and a cover for the inter-member container.

25 4. In a container, in combination, two casings hingedly attached to each other, a plurality of toilet articles carried by the inner faces of the casings and an inter-member between the casing having spaced sides forming a plurality of containers capable of having articles inserted through the top thereof.

30 5. In a container, in combination, two casings hingedly attached to each other, a plurality of toilet articles carried by the inner faces of the casings, an inter-member between the casings having spaced sides forming a plurality of containers capable of having articles inserted through the top thereof and a cover for the inter-member container.

35 6. In a container, in combination, two

casings hingedly attached to each other, a plurality of toilet articles carried by the inner faces of the casings and an inter-member between the casings having spaced sides forming a container capable of having articles inserted through the top thereof, the inter-member being hinged to the casing hinge.

40 7. In a container, in combination, two casings hingedly attached to each other, a plurality of toilet articles carried by the inner faces of the casings, an inter-member between the casings having spaced sides forming a plurality of containers capable of having articles inserted through the top thereof, the inter-member being hinged to the casing hinge and a cover for the inter-member containers.

45 8. In a container, in combination, two casings hingedly attached to each other, a powder compact carried by the inner face of one casing, a plurality of toilet articles carried by the inner face of the other casing and an inter-member between the casings having spaced sides and ends forming a container open at the top.

50 9. In a container, in combination, two casings hingedly attached to each other, a powder compact carried by the inner face of one casing, a plurality of toilet articles carried by the inner face of the other casing, an inter-member between the casings having a plurality of compartments open at the top and a cover for the inter-member compartments.

55 10. In a container, in combination, two casings hingedly attached to each other, a powder compact carried by the inner face of one casing, a plurality of toilet articles carried by the inner face of the other casing, an inter-member hinged to and between the casings having a plurality of compartments open at the top and a cover for the inter-member compartments.

60 Signed at New York city, in the county of New York and State of New York this 12th day of December, 1922.

IDA W. CHERNOFF.
